CLOSING MACHINE

Neils P. Bach, Geneva, N. Y., assignor to American Can Company, New York, N. Y., a corporation of New Jersey

Application January 10, 1939, Serial No. 250,235

4 Claims. (Cl. 113—24)

The present invention relates to a container or can closing machine for crimping metal can ends onto fibre can bodies and has particular reference to a crimping head having eccentrically mounted tapered rollers for performing the crimping operation.

An object of the invention is the provision of a closing machine having a rotatable crimping head wherein tapered rollers housed within the head are used for performing the crimping operation thereby obtaining a more uniform and smoother end seam than that usually obtained with other crimping devices.

Another object is the provision in such a crimping head of devices for laterally adjusting the rollers relative to the can to be closed so that full control may be had over the tightness of the resulting seam.

Numerous other objects and advantages of the invention will be apparent as it is better understood from the following description, which, taken in connection with the accompanying drawings, discloses a preferred embodiment thereof.

Referring to the drawings:

Figure 1 is a sectional view of the principal working parts of a closing machine embodying the instant invention with a can in position ready to be operated on, parts being broken away;

Fig. 2 is an enlarged horizontal sectional view taken substantially along the lines 2—2 in Fig. 1, with parts broken back and other parts broken away; and

Fig. 3 is an enlarged sectional detail of a portion of the crimping head of the machine, the view showing a can raised into the head and being closed thereby.

As a preferred embodiment of the invention the drawings illustrate the principal parts of a can closing machine in which a preferably fibre can A is closed with a metallic can end B secured to the can by a crimping over of a flange part C formed on the can end. The can end is preferably of the countersunk panel type so that a backing may be provided for the end curl when the latter is turned or bent down against the upper edge of the can to form the finished seam.

The machine includes a rotatable crimping head D having a centrally disposed and vertically movable chuck E which is operated in time and in cooperation with a vertically movable lifter plate F. The chuck clamps a positioned can end onto a can to be closed and the lifter plate raises the can and its end into the crimping head for the crimping operation.

The lifter plate F on which the can is supported

is mounted on a vertically disposed rod 11 carried in a bearing 12 formed in a main frame 13 which supports the various parts of the machine. Vertical movement of the lifter plate is effected in any suitable manner in time with the other moving parts of the machine. Centering lugs 14 secured to the lifter plate and engaging around and over the bottom end seam of the can retain the can in a central position on the lifter plate.

10 The chuck E is disposed in vertical alignment with a can A when the can is supported on the lifter plate. This chuck is secured to the lower end of a vertically axial disposed bar or rod 16 which extends through the crimping head D and which is adapted to be lowered and raised in time with the lifter plate.

Vertical movement of the chuck bar is effected by a cam 18 which is keyed to a vertical drive shaft 19 journaled in bearings 21 formed in the main frame 13. Shaft 19 may be the main driving shaft of the machine. Cam 18 is formed with a cam groove 23 in which there operates a cam roller 24 carried on an arm 25 pinned to the lower end of a vertically disposed rod 26 mounted in a long bushing 27 secured in bosses 28 formed on the main frame. The rod 26 extends above the bushing and carries an arm 29 which is secured to a housing 31 slidably mounted on a reduced diameter upper section 32 of the chuck bar 16.

25 The housing 31 constitutes a part of a yieldable unit connection between the chuck bar 16 and its actuating devices just described, which compensates for variations in can heights and which creates a pressure on the chuck E when the latter is brought into engagement with the can end on a can to be closed. The housing 31 encloses a compression spring 34 which is interposed between a nut 35 threaded into the upper end of the housing and a flange 36 of a sleeve 37 carried on the chuck bar end section 32.

30 The sleeve 37 extends up through the nut 35 and its upper end is secured in a collar 38 which rests on a shoulder 39 formed on the chuck bar end 32. An auxiliary compression spring 41 normally holds the collar against its shoulder. A cap screw 42 threaded into the end of the chuck bar retains the spring in place on the collar.

35 Thus when the lifter plate F rises to lift the can A and its superimposed can end B into the crimping head D, the cam 18 through its connection with the chuck bar 16 pulls the chuck E down into the countersunk panel of the can end. This is against the resistance of the spring 34 of the yieldable unit hereinbefore mentioned.

40 45 50 55 55 This creates a pressure on the can end which

tightly clamps the can between the chuck and the lifter plate. As the lifter plate continues to rise, the cam 18 lifts the chuck E in time therewith but maintains the clamping pressure on the can and its end. In this clamped position the can and its end are introduced into the crimping head D.

The crimping head D includes an enlarged and preferably cylindrical body section 51 which is formed on the lower end of a hollow head spindle 52 journaled in a pair of spaced bearings 53 formed in the main frame and also in a ball bearing 54 disposed adjacent the lower bearing 53. The ball bearing 54 is retained in a housing 55 threaded onto the lower end of the lower bearing 53. A shouldered upper section 56 of the head spindle rests on top of the upper bearing 53 and thereby retains the head in place. The chuck bar 16 extends through this hollow head spindle.

The head body 51 carries a plurality of crimping or seaming rollers 61. Each roller has a lower tapered section 62 which merges into an upper straight or cylindrical section 63 which is parallel to the axis of rotation of the roller. These rollers are arranged in a circle concentric with the chuck bar 16. Each crimping roller 61 is freely and concentrically mounted on the lower end of a roller shaft 64 carried in an eccentric bushing or sleeve member 65 disposed in a bearing 66 formed in the head body 51.

The crimping head as a unit is continuously rotated in its bearings 53, 54 by a driving gear 67 (Fig. 1) which is carried on the upper end of the driving shaft 19. Gear 67 drives an idler pinion 68 formed on a gear shaft 69 journaled in bearings 71 in the main frame 13. Pinion 68 is also integral with a gear member 72 which meshes with a gear 73 which in its turn is part of a gear 74. These integral gears 73, 74 are mounted on the long bushing 27. Gear 74 meshes with a head gear 75 formed on the head spindle 52 and thus drives the head.

When the can A and its superimposed can end B are being raised into the rotating crimping head, the projecting curl C of the can end is engaged by the tapered sections 62 of the crimping rollers as best shown in Fig. 3 and is thereby gradually and progressively bent downwardly and inwardly toward the outer wall of the can as the latter continues to move into the crimping head.

Upward movement of the can continues until the bending can end curl is well onto the straight section 63 of the rollers. This straight section of the rollers is of sufficient depth and extent to flatten the bent or formed curl and partially embed the same against and into the can side wall, thereby producing a tight end seam which holds the can end securely onto the can. This completes the can closing or crimping operation.

The closed can is now lowered to its original position by a cooperative lowering of lifter plate F and chuck E. In this action the chuck E strips the closed can out of the crimping head D, the chuck first moving down in time with the lifter plate but only a sufficient distance below the head to insure full release of the can from the head. When in its lowermost position, the can may be removed or discharged from the lifter plate in any suitable manner.

To insure proper tightness of the seam produced in the crimping operation, provision is made for manual adjustment of the rollers 61 relative to the chuck E. Each eccentric bushing

65 has a segment gear 77 secured by screws 78 (Fig. 2) to its upper end. These segment gears mesh with an internal ring gear 79 disposed in a recess 81 formed in the top of the crimping head body 51. The ring gear is held against displacement by a cover plate 82 which is secured along its periphery to the head body by bolts 83.

The bottom surface of the ring gear 79 is provided with bevel gear teeth 84 (Fig. 1) which mesh with a small bevel pinion 85 (see also Fig. 2) disposed in a recess 86 formed in a side of the head body 51. The pinion is mounted on a screw shaft 87 carried in a bearing 88 in the head body and also in a gear retaining nut 89 disposed in the recess and threaded into the adjacent wall of the head body. The outer end of the screw shaft is provided with a slot 91 for application of a screw driver thus permitting manual turning of the bevel gear 85.

By turning of the bevel gear 85 the ring gear 79 is rotated and this rocks the segment gears 77 and the eccentric bushing connected thereto in unison. The roller shafts carried in the bushing are thus laterally shifted in either direction depending upon the direction in which the bevel gear 85 is rotated, and to the desired amount to effect proper adjustment of the crimping rollers 61.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for crimping ends on can bodies, the combination of a rotatable crimping head including a plurality of sleeve members having eccentric bores rotatably carried thereby and spaced equidistant from the axis of said head, means on said sleeve members for rotating the members, a plurality of crimping rollers having concentric shafts respectively mounted in the said bores of said sleeve members, said rollers being adapted to engage the periphery of a can end superimposed on a can body to secure the end to the body in a crimped seam, means for rotating said head, means carried bodily by said seaming head and engaging the rotating means on said sleeve members, and means secured to the head for moving said sleeve engaging means relative to said head when the machine is at rest for selectively rotating said sleeve members on their axes in opposite directions to radially shift said eccentrically mounted roller shafts and said rollers relative to the axis of said head.

2. In a machine for crimping ends on can bodies, the combination of a rotatable crimping head including a plurality of sleeve members having eccentric bores rotatably carried thereby and spaced equidistant from the axis of said head, a segment gear secured to each of said sleeve members, a plurality of crimping rollers having concentric shafts respectively mounted in the said bores of said sleeve members, said rollers being adapted to engage the periphery of a can end superimposed on a can body to secure the end to the body in a crimped seam, means for rotating said head, a ring gear and means to rotatably mount said ring gear on said crimping head to mesh with the segment gears of said sleeve members, and means on the head operable for partially

rotating said ring gear relative to said crimping head selectively in opposite directions when the machine is at rest, for simultaneously rocking said segment gears and said sleeve members on their longitudinal axes, to radially shift said eccentrically mounted roller shafts and said rollers relative to the axis of said head.

3. In a machine for crimping metal ends on fibre can bodies, the combination of a rotatable crimping head including a plurality of sleeve members having eccentric bores rotatably carried thereby and spaced equidistant from the axis of said head, means on said sleeve members to rotate the members, a plurality of crimping rollers having concentric shafts respectively mounted in the said bores of said sleeve members and each including a lower tapered section and an upper cylindrical section having substantially the same diameter as the greatest diameter of the tapered section, said rollers being adapted to engage the periphery of a can end superimposed on a fibre can body to secure the end to the body in a crimped seam, operable means on the head to engage and move the sleeve member rotating means, means for rotating said head, and means for moving said assembled can body and end into operative engagement with said rollers, first with the tapered sections thereof to form the crimped seam between the end and body and thereafter into engagement with the upper cylindrical sections of

said rollers to embed portions of the crimped seam into the fibre wall of the body to complete the seam.

4. In a machine for crimping metal ends on fibre can bodies, the combination of a rotatable crimping head having a plurality of crimping rollers having concentric shafts mounted thereon spaced equidistant from the axis of said head, each of said rollers including a lower tapered section and an upper cylindrical section of substantial extent and having substantially the same diameter as the greatest diameter of the tapered section, said rollers being adapted to engage the periphery of a can end superimposed on a fibre can body to secure the end to the body in a crimped seam, means for rotating said head, means for maintaining said rollers a constant distance radially of the axis of rotation of said head during the crimping operation, and means for moving said assembled can body and end into operative engagement with said rollers, first with the tapered sections thereof to form the crimped seam between the end and body and thereafter into engagement with the upper cylindrical sections of said rollers, said roller cylindrical sections being of sufficient depth to completely flatten the formed seam and embed portions of the same into the fibre wall of the body to complete the seam.
